PIPE VENT

William V. Porter, 1823 S. W.W., White Road,
San Antonio 20, Tex.

Filed Oct. 25, 1962, Ser. No. 72,267

Term of patent 14 years

(Cl. D91—1)

Fig. 1

Fig. 2

Fig. 3

Fig. 4

FIG. 1 is a perspective view of a pipe vent, showing my new design;

FIG. 2 is a front elevational view;

FIG. 3 is a side elevational view; and

FIG. 4 is a bottom plan view.

I claim:

The ornamental design for a pipe vent, as shown.
